UNITED STATES PATENT OFFICE.

FRANK F. LANDIS, OF WAYNESBOROUGH, PENNSYLVANIA.

FEED-WATER HEATER AND PURIFIER.

SPECIFICATION forming part of Letters Patent No. 508,174, dated November 7, 1893.

Application filed March 9, 1893. Serial No. 465,305. (No model.)

To all whom it may concern:

Be it known that I, FRANK F. LANDIS, a citizen of the United States, residing at Waynesborough, in the county of Franklin and State of Pennsylvania, have invented certain new and useful Improvements in Feed - Water Heaters and Purifiers; and I do hereby declare the following to be a full, clear, and exact description of the invention, such as will enable others skilled in the art to which it appertains to make and use the same.

This invention relates to devices for heating and purifying the feed water within the shell of the boiler before it is allowed to pass into contact with the heated furnace plates and tubes which convert it into steam.

This invention consists in the novel construction and combination of the parts hereinafter fully described and claimed.

20 In the drawings: Figure 1 is a longitudinal section through a boiler constructed according to this invention; and Fig. 2 is a cross-section through the same, taken on the line $x-x$ in Fig. 1.

25 A is the shell of the boiler; A' is its fire-box; and a are the heating tubes, connecting the fire-box with the smoke-box a'.

30 B are precipitating and collecting pans arranged in a substantially horizontal series in the steam space of the boiler above the heating tubes. Means for supporting the pans are provided, and may be of any approved construction which will permit the pans to be moved about when desired. Angle irons b are shown riveted to the shell of the boiler as one means for supporting the pans. As an equivalent means of support, the pans may have feet b', as indicated in Fig. 1, adapted to rest on the upper tubes; and many other 40 equivalent forms of supporting devices may be used.

45 C is a hand-hole in the boiler shell. This hole is provided with a cover of any approved construction. The hand-hole is arranged so that, when the cover is removed, the pans can be removed through it, and replaced, one by one. The pans near the fire-box and smoke-box are slid along their supports until opposite the hand-hole, before they are withdrawn.

50 If desired, the removable pans may be placed inside the displacing chamber of the

traction-engine boiler shown and described in the patent issued to me on January 30, 1883, No. 271,477, and the said chamber then forms 55 their means of support. When used in a traction-engine boiler, the pans may however be supported as shown in the drawings, and the pans themselves may form a substitute for the displacing chamber shown in the above-mentioned patent. The pans nearest the smoke-box are then preferably made of greater depth than those nearest the fire-box. The water will then, in a great measure, be prevented 60 from uncovering the crown-sheet of the fire-box when the engine is going down hill. When the traction engine boiler is on level ground the water is above the crown sheet of the boiler fire-box and below the top of the shallowest pan. When the engine is proceeding 65 down a hill the water gravitates to the front end of the boiler and tends to uncover the crown sheet. The deep pans occupy considerable space at the front end of the boiler and partially prevent this movement of the 70 water, so that when the water level comes about parallel with the line of the tops of the pans there will still be sufficient water retained over the crown sheet to prevent it from being overheated. Each pan is made of thin 75 sheet metal and ribs or lugs c are preferably provided on the sides of the pans to keep them at a little distance apart. The pans are prevented from lifting out of place by the curved top portion of the boiler shell, or a 80 stop bar c' may be secured to the shell for that purpose, as shown at the right hand in Fig. 2.

D is the feed-water inlet pipe provided with a check valve d of approved construction; 90 and d' is a blow-off valve, the use of which will be more fully described hereinafter.

E are branch pipes connected to the pipe D between the two valves and projecting within the shell of the boiler. Two branch 95 pipes e are connected to each pipe E inside the boiler, and are arranged horizontally over the pans. The pipes e are provided with nozzles e' over the pans. The area of each nozzle aperture is very small, and each pan is 100 adapted to hold a considerable body of water. The proportions of the parts are preferably so arranged that when the feed pump is at work each pan will be filled in about fifteen

or twenty minutes for the boiler of a traction-engine, as boilers of this class usually work at a steam pressure of about four atmospheres.

The feed-water is injected into each pan, 5 each pan receiving substantially the same amount in the same time. The feed-water descends to the bottom of each pan and is heated nearly to the temperature corresponding to the pressure of the steam in the boiler 10 before it flows over the tops of the pans. The impurities in the water are precipitated in each pan as soon as the temperature of precipitation is reached, and the water is practically pure before it flows over the top edges 15 of the pans. The water in the pans is still and practically motionless except where the small jet of feed water impinges on it, and the precipitation of the impurities and their collection in the bottoms of the pans are therefore 20 greatly facilitated.

When the boiler has been at work for some time, the pans are removed through the hand-hole and are cleaned out.

The impurities of the water are collected 25 by the pans, and the steam-producing surfaces are kept free from scale and dirt. The blow-off valve d' is opened occasionally while the boiler is at work. This permits the steam to pass back through the nozzles and clear 30 them and the pipes of any solid matter which might collect and choke up the nozzles.

The device is applicable to many other forms of boiler besides that shown in the drawings.

35 What I claim is—

1. The combination, with the shell of a boiler, of a series of pans supported in the steam space of the boiler each pan operating to retain a considerable body of still water, 40 and a feed-water pipe provided with a sepa-

rate nozzle for each pan, said nozzles having very small discharge openings and operating to supply the pans slowly and uniformly, whereby the impurities are precipitated and collected in the pans, substantially as set 45 forth.

2. The combination, with the shell of a boiler provided with a hand-hole, of a series of removable pans for receiving the feed-water said pans being arranged side by side horizontally and adapted to be slid longitudinally of the boiler, and means for supporting the said pans in the steam space of the boiler and permitting their removal through the said hand-hole, substantially as set forth. 50

3. The combination, with a boiler provided with a fire-box, a smoke-box and heating tubes substantially as set forth; of a series of pans for receiving the feed water, supported in the steam space above the tubes, the pans near 60 the smoke-box being of greater depth than those near the fire-box, substantially as described and shown.

4. The combination, with the shell of a boiler, and a series of pans supported in its steam space; of a feed-water pipe provided with a separate nozzle over each pan the said nozzles having very small discharge openings and operating to supply the pans slowly and uniformly, and a blow-off valve secured 70 to the feed-water pipe, whereby solid matter accumulating in the said pipe or nozzles may be blown out by the steam, substantially as set forth.

In testimony whereof I affix my signature in 75 presence of two witnesses.

FRANK F. LANDIS.
